(57) CLAIM

The ornamental designs for a hair ornament, as shown and described.

DESCRIPTION

FIG. 1 is a front perspective view of a hair ornament showing my new design;

FIG. 2 is a side elevational view thereof;

FIG. 3 is an end elevational view thereof;

FIG. 4 is a perspective view of a second embodiment of a hair ornament showing my new design, the only difference being the bead, the partial view disclosing the bead is drawn for ease of illustration;

FIG. 5 is a perspective view of a third embodiment of a hair ornament showing my new design, the only difference being the bead, the partial view disclosing the bead is drawn for ease of illustration;

FIG. 6 is a perspective view of a fourth embodiment of a hair ornament showing my new design, the only difference being the bead, the partial view disclosing the bead is drawn for ease of illustration; and,

FIG. 7 is a perspective view of a fifth embodiment of a hair ornament showing my new design, the only difference being the bead, the partial view disclosing the bead is drawn for ease of illustration.
